UNITED STATES PATENT OFFICE.

LAWRENCE W. COLTON, JOSEPH LA PORTE, AND THEODORE W. COOKE, OF LONG BEACH, CALIFORNIA; SAID LA PORTE ASSIGNOR TO SAID COLTON AND SAID COOKE.

SWAB.

Application filed October 12, 1923. Serial No. 668,073.

This invention relates to deep well apparatus and more particularly to swabs.

The general object of the present invention is to provide a highly efficient and at the same time practicable and simple swab; also to provide a swab including one or more compressible and expandable packing members, with means for securing the same at any point on their supporting stem, and for compressing them so as to make a tight sliding fit in a well casing or pump tube.

Further objects of the invention will appear hereinafter.

The invention consists in the novel parts and combinations of parts to be described hereinafter, all of which contribute to produce an efficient swab.

A preferred embodiment of the invention is described in the following specification, while the broad scope of the invention is pointed out in the appended claims.

In the drawings:

Figure 1 is a side elevation of the swab shown as arranged in a casing indicated in section.

Fig. 2 is a perspective of one of the expandable packing members.

Fig. 3 is a perspective of a packing member thimble.

Fig. 4 is a central longitudinal section of the upper portion of the swab, and

Fig. 5 is a similar view of the lower portion of the swab.

Swabs of the kind herein concerned include a piston-like apparatus having a valve so that when the piston or plunger is lowered, liquid in the well will pass up beyond the valve and then when the plunger or piston is pulled, a column of the liquid will be carried up thereby.

In practicing our invention we provide a tubular central body or stem 2 which is preferably corrugated or threaded externally at substantially throughout its length. On the lower end is provided a guide 4 having an open lower end to provide for inflow of liquid in the well into the tubular body 2 and up past a check valve 5 in the form of a ball arranged in a cage 6, which is threaded at 7 on a head block 8, threaded at 9 on the upper end of the body 2.

The stem 2 is preferably imperforate. Mounted upon it is one or more elastic packing sleeves 10, preferably made of rubber of

a suitable degree of density; at their inner sides these sleeves engage the threads of the stem. The outer cylindrical surface 10^a of each stem is set firmly against the tubing or casing C, Figure 1, in the well to be swabbed. The packing members 10 are adapted to be compressed longitudinally and therefore expanded laterally so as to take up wear and maintain a good tight joint in the pipe, tube or casing C.

We provide means between the sleeves for compressing them.

It is preferable to employ a plurality of packing members mounted in a series on the stem. This is a most advantageous construction because, as frequently happens, particularly in wells drilled by the rotary method, the tubing is not preferably straight and has "bends" in it. In moving a long sleeved swab past such a bend there is a tendency for it to stick, and when a short swab moves past such a bend the bend is apt to cause considerable leakage past the swab. By having a plurality of packing members the swab readily passes through such a bend because it accommodates itself readily to the bent form of the tube, and therefore more effectively prevents leakage past the swab at such a point. Furthermore, by employing a plurality of packing members I can obtain an increased swabbing area without being obliged to make the length of the packing member so great as to interfere with effectively securing it to the stem.

A practical and effective form of means for compressing and expanding the packer members 10 consists of thimbles 11, one against each end of each packer, these latter being provided with reduced end portions 10^b fitting inside the thimbles 11. The thimbles are designed to slide freely over the threaded body 2 and are set up by threaded members such as spanner nuts 12 which operate to compress the packers 10, longitudinally after which the spanner nuts are jammed by lock nuts 13. Compressing the sleeves 10 causes their inner faces or bores to press into the threads of the stem 2 and this holds the sleeves securely in place.

From the above it will be seen that the swab includes one or more expandable packing members 10 which are adapted to be readily laterally expanded so as to bear snugly against the inner surface of the pipe,

tube or casing C and therefore prevent the escape of liquid in the casing when the swab is being pulled up after it has been lowered to the desired degree to trap a body of the liquid in the casing C.

Further embodiments, modifications and variations may be resorted to within the principle of the invention.

What is claimed is:

10. 1. A swab for well tubing comprising a central tubular stem, an elastic packing member mounted on said stem, said stem being corrugated on its outer surface all along the place where the packing member is mounted, and means circumferentially embracing the upper end of said packing member.
2. A swab for well tubing comprising a central tubular stem, an elastic packing member mounted on said stem, said stem being threaded all along the place where the packing member is mounted, and means including threaded members and members circumferentially embracing the ends of said elastic packing for longitudinally compressing and laterally expanding said packing member.
3. A swab for deep well operations including a tubular central stem threaded externally, expansible packing members mounted on the said stem, the packing members being arranged so that their entire inner surfaces are in contact with the threaded portions of the stem, thimbles mounted on the stem to separately engage both ends of each packing member, and threaded members op-

erating on the threaded stem to clamp the thimbles against the packing members.

4. A swab for deep well operations including a tubular central stem threaded externally, expansible packing members mounted on the said stem, the packing members being arranged so that their entire inner surfaces are in contact with the threaded portions of the stem, thimbles mounted on the stem to separately engage both ends of each packing member, and threaded members operating on the threaded stem to clamp the thimbles against the packing members, one of said threaded members being located between each two adjacent thimbles to compress and expand each packing member independently of the other packing members.

5. In a swab for deep well operations, the combination of an imperforate tubular central stem threaded externally, a plurality of expansible packing members mounted on the stem and engaging the threads of the stem at their inner sides, a plurality of thimbles mounted on the stem operating to engage both ends of the packing members, and threaded members mounted on the threaded stem some of which threaded members are located between said packing members for independently expanding the packing members.

In testimony whereof we have signed our names to this specification.

LAWRENCE W. COLTON.

JOSEPH LA PORTE.

THEODORE W. COOKE.
